COSMETIC CASE

John J. Territo, 1707 E. Missouri, Phoenix, Ariz.

Filed Apr. 23, 1965, Ser. No. 84,940

Term of patent 14 years

(Cl. D87—5)

FIG. 1 is a front isometric view of a cosmetic case showing my new design, in closed condition;

FIG. 2 is a similar view, but showing the case in open condition;

FIG. 3 is a top plan view thereof;

FIG. 4 is a left-side elevational view thereof, the right side being a mirror image thereof; and

FIG. 5 is a front elevational view thereof.

I claim:

The ornamental design for a cosmetic case, as shown and described.
